UNITED STATES PATENT OFFICE

2,518,004

HIGHWAY GUARD STRUCTURE BRACKET

Nevil Greenwell, Bethlehem, Pa., assignor to
Bethlehem Steel Company, a corporation of
Pennsylvania

Application March 16, 1945, Serial No. 583,132

9 Claims. (Cl. 248—66)

1

My invention relates to improvements in guard structures for highways and especially to brackets for resiliently supporting the guard with respect to the supports.

One object of my invention is to provide improved brackets for a highway guard structure which will effectively resist impacts transmitted to the guard structure by travelling vehicles coming into contact with the guard structure so as to prevent the vehicles from leaving the highway, and which at the same time will effectively absorb the shock transmitted by such vehicle to the guard structure so that the vehicle will receive no substantial damage upon impact with the guard.

Another object of my invention is to provide improved brackets intermediate the guard and the supports which will effectively support the guard in spaced relation to the supports at all times.

The novel features of my invention will be more fully understood from the following description and claims taken with the accompanying drawings in which

Figure 1 is a top plan view of a section of a highway guard structure embodying one form of my invention.

Fig. 2 is a side view in elevation of the structure shown in Fig. 1.

Fig. 3 is an enlarged sectional view taken on line 3—3 of Fig. 5.

Fig. 4 is a top plan view of the bracket shown in Fig. 3 in its deformed condition.

Fig. 5 is a side view in elevation of the structure shown in Fig. 3.

Fig. 6 is a top plan view of a bracket embodying a modification of my invention.

Fig. 7 is a rear view in elevation of the bracket shown in Fig. 6.

Referring to the drawings, particularly Fig. 1, I show a highway guard structure comprising a plurality of supports or posts 16 having a plurality of guard cables 17 supported thereon through the medium of my improved brackets 18 and one of the end or anchor posts 19, to which one end of the guard cables 17 are anchored. The brackets shown in Figs. 1 and 2, an enlarged view of one of which is shown in Figs. 3, 4 and 5 are shown connected to the supports 16 by means of bolts 20 and the guards 17 are shown slidably connected to the brackets 18 by means of the clips 21, which, while shown in these figures as having their lower ends 22 inserted in slots 23 in the brackets 18 and their upper end secured to the bracket 18 by the bolts and nuts 24, may be connected to the brackets 18 in any well known manner. The guards 17, as shown, comprise cables which are preferably slidably mounted in loops 25 provided in the clips 21.

Referring particularly to Figs. 3, 4 and 5, the

2

bracket 18 comprises support or post engaging leaf spring portions 26 and 27 which are shown united by a weld and which diverge outwardly from the weld towards their end portions 28 and 29, respectively, and provide camming surfaces, an inverted U-shaped guard engaging portion 30, comprising legs 31 and 32, and reversely curved portions 33 and 34 intermediate the leg 31 and the end portion 28 and the leg 32 and the end portion 29, respectively, these reversely curved portions comprising C-shape portions 35 and 36 and arcuate portions 37 and 38, respectively. An opening 39 is provided in the leaf spring portions 26 and 27 for receiving the bolt 20 to secure the bracket 18 to the support 16. While the post engaging leaf spring portions are shown welded together any other connecting means may be used to connect these portions without departing from the scope of my invention.

The bracket 40 shown in Figs. 6 and 7 is similar to the bracket disclosed in Figs. 3, 4 and 5. The bracket 40 comprises support or post engaging leaf spring portions 41 and 42 which are shown united by a weld 43 and which have lips 44 deflected inwardly thereof which provide portions diverging outwardly toward the end portions 45 and 46, respectively, an inverted U-shaped guard engaging portion 47, comprising legs 48 and 49, reversely curved portions 50 and 51 intermediate the leg 48 and the end portion 45 and intermediate the leg 49 and the end portion 46, respectively, these reversely curved portions comprising C-shaped portions 52 and 53 and arcuate portions 54 and 55, respectively. An opening 56 is provided in the leaf spring portions 41 and 42 for receiving the bolt 20 to secure the bracket 40 to the supports. As stated with reference to the bracket 18 the support engaging leaf spring portions while shown welded together, may be joined in any suitable manner.

In operation, when a vehicle comes into contact with considerable force with the guard cables 17, the U-shaped portion 30 of the guard cable bracket 18 will move inwardly until the end of the legs 31 and 32 or the arcuate portions 37 and 38, respectively, contact the leaf spring portions 26 and 27, respectively, as shown in full lines in Fig. 4, and due to the inclination of the leaf spring portions 26 and 27 the continued force transmitted to the U-shaped portion 30 will cause these arcuate portions 37 and 38 to move down these inclinations in opposite direction and will move the legs 31 and 32, respectively, outwardly with respect to each other, as shown in dotted lines in Fig. 4. During the initial movement of the U-shaped portion 30 inwardly towards the leaf spring portions 26 and 27, the C-shaped portions 35 and 36, respectively, will have a tendency to coil towards each other in absorbing the impact of the vehicle with the guard cable 17 but

upon contact of the arcuate portions 37 and 38, respectively, with the leaf spring portions 26 and 27, the arcuate portions 37 and 38, respectively, will have a tendency to uncoil away from each other due to the movement of the legs 31 and 32 away from each other, during the further deflection of the bracket. The provision of means for deflecting the legs of the bracket after partial deformation thereof is an important feature of this invention as it provides a bracket which throughout its operation effectively absorbs the shock imparted to the guard cable 17 upon the impact of the vehicle therewith.

The operation of the bracket 40 shown in Figs. 6 and 7 is substantially the same as the operation of the bracket 18, except that under impact the U-shaped portion 47 of the bracket will move inwardly until the end of the legs 48 and 49 or arcuate portions 54 and 55, respectively, contact the lips 44, and due to the inclination of these lips 44 the continued force transmitted to the U-shaped portion 47 will cause the arcuate portions 54 and 55 to move down the inclined lips 44 away from each other and thereby move the legs 48 and 49 outwardly with respect to each other, and the action of the C-shaped and arcuate portions therefore will be the same as the similar portions of the bracket 18, as shown in Fig. 4. While I have shown my invention in a plurality of forms it will be obvious to those skilled in the art that it is not so limited, but is susceptible of various other changes and modifications without departing from the spirit thereof, and I desire therefore, that only such limitations shall be placed thereupon as are imposed by the prior art or as are specifically set forth in the appended claims.

Having thus described my invention, what I claim as new and desire to secure by Letters Patent is:

1. A bracket for a highway guard structure comprising a leaf spring support engaging portion, a U-shaped guard engaging portion and arcuate portions intermediate the support engaging portion and the U-shaped portion, said arcuate portions having their outer ends connected to the support engaging portion and their inner ends extending inwardly towards said support engaging portion but terminating in spaced relation thereto and connected to the guard engaging portion.

2. A resilient bracket for a highway guard structure comprising an inverted U-shaped guard engaging portion having substantially parallel legs, a leaf spring portion comprising a support engaging portion and a pair of inwardly extending portions, said inwardly extending portions being connected to said legs, respectively, and in cooperation with said support engaging portion to deflect the legs of said U-shaped portion outwardly during the inward movement of said U-shaped portion towards said support, and resilient C-shaped portions intermediate the U-shaped portion and the leaf spring portion.

3. A resilient bracket for a highway guard structure comprising an inverted U-shaped guard engaging portion having substantially parallel legs, a leaf spring portion comprising a support engaging portion and a pair of inwardly extending portions, said inwardly extending portions being connected to said legs, respectively, and in cooperation with said support engaging portion to deflect the legs of said U-shaped portion out-

wardly during the inward movement of said U-shaped portion towards said support, and resilient C-shaped portions intermediate the U-shaped portion and the leaf spring portion, and arcuate portions connecting the legs of the U-shaped portion and the C-shaped portions.

4. A guard bracket comprising an inverted U-shaped guard engaging portion, leaf spring portions having their extremities connected to provide a support engaging portion having its intermediate portion extending inwardly towards said U-shaped portion to constitute camming surfaces and deformable arcuate portions connecting said U-shaped portion and said leaf spring portions.

5. A highway guard bracket comprising a base portion, a pair of leaf springs connected to the base portion and having their respective outer ends extending inwardly towards the base portion but terminating in spaced relation thereto, and a pair of legs joined together at one of their ends and connected at their opposite ends to said outer ends respectively.

6. A highway guard bracket comprising a base portion having a pair of camming surfaces, a pair of leaf springs connected to the base portions and having their outer ends disposed in opposite relation to said camming surfaces respectively, and a pair of legs joined together at their outer ends and connected at their inner ends to said outer ends of said leaf springs respectively.

7. A highway guard bracket comprising a base portion having a pair of camming surfaces, a pair of C-shaped leaf springs connected to the base portions and having their outer ends disposed in opposite relation to said camming surfaces respectively, and a pair of legs connected at one of their ends and connected at their other ends to said outer ends respectively.

8. A bracket for a guard rail and the like comprising a support engaging element, a rail supporting portion in spaced relation to said element, said rail supporting portion comprising legs integral therewith and extending toward said element, and oppositely disposed spring members extending outwardly from the ends of said legs and inwardly to connect said legs to said element.

9. A bracket for a guard rail and the like comprising a support engaging element, a rail supporting portion in spaced relation to said element, said rail supporting portion comprising legs integral therewith and extending towards said support engaging element, deflecting means for said legs in cooperation with said support engaging element and oppositely disposed spring members connected to and extending outwardly from said legs respectively and inwardly and connected to said support engaging element.
